CLIO B. YAW, OF ARLINGTON, NEW JERSEY, ASSIGNOR TO REMINGTON TYPEWRITER COMPANY, OF ILION, NEW YORK, A CORPORATION OF NEW YORK.

TYPE-WRITING MACHINE.

1,012,785.

Specification of Letters Patent. Patented Dec. 26, 1911.

Application filed November 19, 1909. Serial No. 528,965.

To all whom it may concern:

Be it known that I, Clio B. Yaw, citizen of the United States, and resident of Arlington, in the county of Hudson and State of New Jersey, have invented certain new and useful Improvements in Type-Writing Machines, of which the following is a specification.

My invention relates to typewriting machines and more particularly to work registering mechanism for such machines.

Sometimes operators are paid by piece work and it is desirable to provide some kind of a check upon the operators other than by a rigid inspection and keeping of separate accounts of the actual work done by the different operators. Then again proprietors are sometimes anxious to keep track of the amount of work done by different operators without each operator knowing just how much work has been done by each of the other operators. Heretofore it has been common to provide automatically actuated word counters usually actuated by the space key of the machine and intended to register a number of words written as represented by the actuation of the space key, counting a word for each space or each actuation of the space key. These and all prior word counting devices are open to objections. Thus, the operator at all times knows how much is registered on the machine and how much work is registered on every other operator's machine. Moreover, it is a simple matter in such machines to repeatedly actuate the space key and thus operate the indicator to register one word written for each actuation of the space key without there being any work produced. Then again, in all such word counting constructions, so far as I am aware, the word register was actuated by the printing keys or by the space key; thus placing additional work upon these keys and affecting the "touch."

The objects of my invention are to overcome the above and other difficulties and to provide simple and efficient work registering mechanism by which an indication of the number of words or lines written upon the machine may be determined only by those persons who are in possession of the "key number."

To the above and other ends which will

hereinafter appear, my invention consists 55 in the features of construction, arrangements of parts and combinations of devices to be hereinafter described and particularly pointed out in the appended claims.

In the accompanying drawings wherein 60 like reference characters indicate corresponding parts in the various views, Figure 1 is a vertical central fore and aft sectional view of a No. 10 Remington machine embodying my invention, a sufficient number 65 of parts of the machine being shown to illustrate my invention in its embodiment therein. Fig. 2 is an enlarged detail fragmentary plan view partly in section of the work registering mechanism and some of 70 the associated parts. Fig. 3 is a transverse sectional view of the work register taken on the line $x-x$ of Fig. 4 and looking in the direction of the arrow at said line. Fig. 4 is a longitudinal sectional view of 75 the work register taken on the line $y-y$ of Fig. 3 and showing the work register and some of the associated parts.

I have shown my invention embodied in the present instance in a No. 10 Remington 80 machine, although some of the parts are only conventionally represented in the drawings. It should be understood, however, that the invention may be embodied in various styles of typewriting machines. 85

The frame of the machine comprises a base 1, corner posts 2 and a top plate 3. Key levers 4 are fulcrumed at 5 and are provided with the usual finger keys 6. Each key lever is connected to a link 7 which in turn 90 is connected to a sub-lever 8. The rear end of each sub-lever is connected to a pull link 9 which in turn is pivoted to a type bar 10. The type bars are mounted to strike upwardly and rearwardly against the front 95 face of a platen 11. A universal bar 12 extends transversely beneath the key levers and is supported at its ends on upwardly extending links 13 pivoted at 14 to rearwardly extending arms 15 which project 100 from a rock shaft 16 mounted in bearings in the base 1 of the machine. A centrally disposed, rearwardly extending arm 17 on the rock shaft is connected to a link 18. The upper end of the link 18 is connected 105 to a forwardly extending arm 19 of a dog rocker 20 mounted upon a rock shaft 21. A contractile spring 22 is connected at one

end to a bracket plate 23 which supports the dog rocker and is connected at its opposite end to a projection 24 on the dog rocker. The dog rocker carries at its upper end a feed dog 25 pivoted at 26 (see Fig. 4) to the dog rocker. A spring 27 normally maintains the feed dog 25 in the operative position shown in Fig. 4. The feed dog, however, is adapted to be moved downwardly 10 out of operative position against the pressure of the spring 27 as will hereinafter more clearly appear.

The platen 11 is carried by a carriage 28 mounted on roller bearings 29. Lugs 30 are secured to the carriage and have rearwardly extending arms 31 pivoted thereto. A feed rack 32 is secured to the rear ends of the arms 31 and meshes with a feed pinion 33. This pinion is secured to the forward end of 20 a shaft 34 mounted to turn in a bearing 35 secured by screws 36 to the top plate of the machine. A hub 37 is secured by screws 38 to the rear end portion of the shaft 34 and is provided with a central web portion 39 to 25 which escapement wheels 40 and 41 are secured for relative adjustment by screws 42. Both escapement wheels are thus fixed to rotate with the shaft 34 during the travel of the carriage in both directions. It should be 30 understood that the letter space movements of the carriage from left to right are effected by the intermittent actuations of the feed dog 25, as the feed dog moves forwardly and back between the escapement wheels. 35 When, however, the carriage is returned to the right the escapement wheels will receive a backward rotation and the feed dog will be moved away from the escapement wheel and against the pressure of its spring 27 by 40 the contact of the rear inclined faces of the teeth of the engaged escapement wheel with the rear face of the feed dog. The parts thus far described correspond substantially to those embodied in the No. 10 Remington machine and further detailed description thereof is deemed unnecessary.

The rear end of the hub 37 of the duplex escapement wheel is provided with a beveled wheel 43 which meshes with a corresponding 45 beveled pinion 44 fixed to a hollow shaft 45. From an inspection of Fig. 4 it will be seen that the hollow shaft is supported upon a shaft 46 contained within the hollow shaft and bearing at one end as at 47 in an opening 50 in a bracket arm 48 bent up and forming part of a bracket plate 49 secured to the top plate of the machine by screws 50 and 51. The opposite end portion of the shaft 46 is supported in a bearing 52 of a cylindrical housing 53 which contains register 55 wheels 54, 55, 56, 57, 58. The register in the present instance is shown as a "Veeder cyclometer" although any other suitable form of register may be employed. The cylindrical housing 53 is secured to the bracket 60 plate 49 by a screw 59 and is provided with a sight opening 75 through which the markings on the register wheels may be seen. The hollow shaft 45 is provided with a cylindrical housing 60 closed at one end by a disk 70 61 which connects the housing to the hollow shaft and bearing at its opposite end against the fixed housing 53. This cylindrical housing 60 contains two pawls, one a pawl 62 pivoted on a headed screw 63 to an end of 75 the fixed housing 53 and mounted so that the force of gravity will maintain the engaging nose of the pawl in engagement with a ratchet wheel 64 formed on the shaft 46 and contained within the cylindrical housing 60. 80 The second pawl 65 is contained within the housing 60 and is pressed into engagement with the ratchet wheel 64 by a spring 66 secured at 67 to the housing 60 and pivoted to the disk 61 thereof on a shouldered headed 85 screw 68. From an inspection of Fig. 3 it will be seen that these pawls extend in opposite directions, and the pawl 62 being carried by the fixed casing engages the ratchet wheel and prevents a rotation of the ratchet 90 wheel, and the shaft 46 forming a part thereof, in a direction opposite to that indicated by the arrow in Fig. 3. On the other hand, the pawl 65 is carried by the hollow shaft 45, or the housing 60 connected therewith, and when said shaft is rotated in the direction of the arrow in Fig. 3, the pawl 65 will cause the shaft 46 to be rotated in the same direction. The shaft 46 extends centrally through the housing 53 and the shaft 100 is fixedly connected at its outer end with an eccentric 69 by which motion is transmitted to a gear 70 which surrounds the eccentric and this gear in turn transmits motion to a gear 71 carried by the first of the register 105 wheels 54. A part of the gear 70 likewise meshes with a gear 72 fixed to the inner bearing portion 73 of the fixed housing 53. 110

The gears 71, 72 and 70 constitute differential gearing which causes, in the example shown, a single movement of the register wheel 54 from one number 74 to the next for each fifteen revolutions of the shaft 46 in the direction of the arrow in Fig. 3. The shaft 46 and wheels controlled thereby are 115 prevented from rotating in an opposite direction, as hereinbefore explained, by the pawl 62. Carrying wheels 76 are mounted on a shaft 77 fixed at one end in the fixed gear 72 and fixed at its opposite end in the 120 opposite end wall of the fixed housing 53. These carrying wheels are of the usual construction and mesh with gears on the register wheels to successively actuate them in the well known manner. The cyclometer or 125 register in the construction shown in the present instance is so arranged that the units wheel 54 will be turned from one number to another during the writing of forty words calculating the five spaces to a word. 130

In other words, it requires two hundred strokes on the printing keys or space key to add one to the register so that one will be added to the register for each two hundred 5 strokes on the printing or space key. This number may be readily varied either by changing the character of the Veeder cyclometer employed or by changing the gearing by which motion is transmitted to the 10 cyclometer or register. Thus, by changing the relation of the gears 43 and 44 the number of key operations required to add one to the register may be varied.

From the foregoing description it will be 15 understood that the register is only actuated by an operation of the escapement mechanism and cannot be actuated in any other manner. It will likewise be understood that the register is only actuated during the letter 20 space movement of the carriage from right to left or in the direction of its feed by its spring drum 78 and band 79 and this only when the carriage is under control of its escapement mechanism. If, for instance, 25 the carriage be moved through a tabulator or otherwise than through the control of the escapement mechanism, it is necessary to disengage the feed rack 32 from its escapement pinion 33 and this disengagement 30 is effective to disconnect the carriage from the register so that the movements of the carriage at this time do not affect the register. Moreover, it will be seen that the register is actuated by the power employed to 35 move the carriage and that the work of actuating the register is not borne by the finger keys so that the "touch" of the keys is not affected. It will likewise be seen that it would require as much work on the part of 40 the operator to run up the register with the space key as would be required to actually produce a corresponding amount of work upon the machine as each actuation of the space key corresponds only to the imprint of 45 a single letter.

It will be understood therefore that I have provided simple, comparatively cheap and efficient means for registering work produced upon the machine without persons being able to determine the amount of 50 work produced unless they are in possession of the "key number". Unless, for instance, the operator knows that in the particular example indicated the adding of one to the 55 register represented the writing of forty words, then the operator would not know how to calculate from the register the amount of work produced, and yet the proprietor or other person in possession of the 60 "key number" would at a glance be able to tell just how much work had been performed by the operator.

Various changes may be made without departing from the spirit and scope of my invention.

What I claim as new and desire to secure by Letters Patent, is:—

1. In a typewriting machine, the combination of a power driven carriage, an escapement for controlling said carriage, and a 70 register actuated by the power employed to move the carriage and under the control of said escapement and during the step by step letter space movements of said carriage and operable progressively throughout a plural 75 ity of travels of the carriage.

2. In a typewriting machine, the combination of a power driven carriage, escapement mechanism therefor, a register, and means controlled by the power employed to move 80 the carriage during its step by step letter space movements and operable on the register only when the carriage is moved under control of said escapement mechanism.

3. In a typewriting machine, the combination of a carriage, a feed rack, an escapement and a register actuated by the feed rack under control of said escapement during the movement of the latter of the letter feed direction.

4. In a typewriting machine, the combination of a power driven carriage, an escapement therefor, a register, and means controlled by the escapement, during the letter feeding operations only, to actuate said 85 register.

5. In a typewriting machine, the combination of a power driven carriage, an escapement wheel therefor, means for rotating said escapement wheel during the travel of the 100 carriage in both directions, feed dog mechanism which at all times controls the rotation of said wheel in letter feed direction, a register, and means operable by said escapement wheel during its rotation in the letter 105 feed direction only for actuating said register.

6. In a typewriting machine, the combination of a power driven carriage, an escapement wheel therefor, a register, and gearing 110 intermediate said escapement wheel and register to effect an actuation of the register when the escapement wheel turns to effect a letter space movement of the carriage.

7. In a typewriting machine, the combination of a power driven carriage, an escapement wheel therefor, a register, gearing connected with said escapement wheel and by which the register is actuated, and pawl and ratchet mechanism intermediate said gearing 115 and register to afford a backward rotation of the escapement wheel independently of the register and to cause an actuation of the register during the forward movement of the escapement wheel.

8. In a typewriting machine, the combination of a power driven carriage, an escapement wheel therefor, a register, gearing connected with said escapement wheel and by which the register is actuated during the let- 120 125

- ter space movement of the carriage, a ratchet wheel operatively connected with said register, a driving pawl coöperative with said ratchet wheel and which is turned by said 5 gearing, and a holding pawl coöperative with said ratchet wheel to prevent a backward rotation thereof.
9. In a typewriting machine, the combination of a power driven carriage, register 10 wheels, and means controlled by the letter space movement only of the carriage for turning said register wheels, the travel of the carriage in the opposite direction being ineffective to actuate the register.
- 15 10. In a typewriting machine, the combination of a power driven carriage, escapement mechanism therefor, a register wheel, and means whereby the register wheel is automatically turned from one indication to 20 another on the register wheel but once for a plurality of letter space movements of the carriage in the direction of the feed wheel produced under control of said escapement mechanism.
- 25 11. In a typewriting machine, the combination of a power driven carriage, escapement mechanism therefor, a register wheel, and means whereby the register wheel is automatically turned from one indication to 30 another on the register wheel but once for a plurality of complete travels of the carriage in the direction of its feed and only when they are produced under control of said escapement mechanism.
- 35 12. In a typewriting machine, the combination of a carriage, escapement mechanism therefor, a register wheel, and means operative to turn said register wheel only when the carriage receives letter space movements 40 in the direction of its feed under control of said escapement mechanism.
13. In a typewriting machine, the combination of a carriage, escapement mechanism therefor including an escapement wheel, a register wheel, and means operative to turn said register wheel only when the carriage receives letter space movements in the direction of its feed under control of said escapement mechanism, said means comprising 45 gearing and pawl and ratchet mechanism intermediate said escapement wheel and register wheel.
14. In a typewriting machine, the combination of a power driven carriage, escapement mechanism therefor including an escapement wheel and feed dog mechanism which at all times controls the rotation of said wheel in letter feed direction, a register wheel, and intermediate connections between the escapement wheel and said register 50 wheel, said connections comprising gearing and pawl and ratchet mechanism operative to turn the register wheel during the movement of the carriage in the direction of its feed and inoperative to turn the register 55 wheel during the travel of the carriage in the opposite direction.
15. In a typewriting machine, the combination of a traveling paper carriage, a series of keys, an intermittently advancing 70 shaft connected to said carriage, a register, and means for operating said register from said intermittently advancing shaft under the control of said keys.

Signed at the borough of Manhattan, city 75 of New York, in the county of New York, and State of New York this 18th day of Nov., A. D. 1909.
